COMBINATION SHAVING KIT AND
SHARPENER

Emil Peterson, Jamestown, N. Dak.

Application March 19, 1936, Serial No. 69,694

4 Claims. (Cl. 51—211)

This invention relates to a combination of parts adapted for use in sharpening razor blades, knife blades, scissors or the like adapted jointly for use as a kit to hold a lightweight cup or shaving mug to minimize the danger of upsetting, and which cup or mug in turn may hold a safety razor, tube of shaving cream, a shaving brush or other accessories, when not in use. One of the sections of the device preferably contains compartments for holding safety razor blades.

The more specific objects and advantages will become apparent from a consideration of the description following taken in connection with accompanying drawing illustrating an operative embodiment.

In said drawing:—

Figure 1 is a side elevation of the device with one of the end caps removed;

Figure 2 is a side elevation, and

Figure 3 is a substantially central longitudinal sectional view.

Referring specifically to the drawing wherein like reference characters designate like or similar parts, two sharpener sections are employed at 16 and 11, separate from each other, having concave cylindrical surfaces at 12 and 13, respectively. Such surfaces 12 and 13, collectively provide a round space or well for holding a cup or shaving mug, of light material, such as of aluminum, bakelite, hard rubber or the like. Such cup in turn may hold a safety razor, a tube of shaving cream and a shaving brush or other accessories, when not in use. To insure registry of said walls 12 and 13, the sections 10 and 11 have overlapping or interengaging flanges at opposite sides thereof as at 14 and 15 respectively.

Said sections 10 and 11 are normally held together by removable end caps 16 having continuous flanges 17 whose inner wall conforms to the exterior shape of the sections. These caps 16 may be made of glass, metal or any suitable material.

Reverting to the sections 10 and 11, they are made of any material which will strop, hone, or sharpen metal-edge tools. They may, for instance, be made of glass, or of even more abradant material if desired. For instance the surface 13 is adapted to hone flexible razor blades while the surface 12 is adapted to strop such flexible razor blades. Straight edged razors or knives, usually non-flexible, may be sharpened on the flat surface 18 of section 10, such surface honing the blade or knife. A coarser sharpening surface for knives or the like is provided at the flat surface 19 of the section 11.

At the sides of the sections, they are longitudinally grooved or cut-away as at 20 to provide surfaces for sharpening scissors or the like, the

same having the proper bevel to give the desired edge on the scissors when the blades are moved back and forth in the spaces 20.

The section 11 is preferably provided with one or more compartments as at 21 to retain razor blades or the like.

Both of the caps 16 may be readily removed or just one of them removed, and in addition, the sections 10 and 11 may be separated and individually used.

The device may be used especially in a position with either the surfaces 18 or 19 resting on a table, the weight of the device usually being sufficient to maintain the same in operative position. In addition, the device can easily be held in the hand during the acts of honing, stropping or sharpening.

Various changes may be resorted to provided they fall within the spirit and scope of the invention.

I claim as my invention:—

1. A device of the class described comprising separable sharpening sections, said sections having communicating cutaway spaces adapted to retain a receptacle, the walls in said spaces being sharpening surfaces, interfitting projections on said sections, and grooves on the sides of said sections to facilitate sharpening of special instruments.

2. A device of the class described comprising separable sharpening sections, said sections having communicating cutaway spaces adapted to retain a receptacle, the walls in said spaces being sharpening surfaces, interfitting projections on said sections, and grooves on the sides of said sections to facilitate sharpening of special instruments, and end caps telescopically engaging said sections.

3. A device of the class described comprising interfitting sections of abrading material, said sections having communicating hemispherical spaces to accommodate a receptacle, the walls in said spaces serving for sharpening purposes, and a removable section applied to the first mentioned section.

4. A device of the class described comprising interfitting sections of abrading material, said sections having communicating hemispherical spaces to accommodate a receptacle, the walls in said spaces serving for sharpening purposes, and a removable section applied to the first mentioned section, one of said walls being a stropping wall and the other being a honing wall, said first and second sections having flat walls one being a honing wall and the other being of coarser material.

EMIL PETERSON.
